UNITED STATES PATENT OFFICE.

CARLTON W. HOLMES, OF LONG BEACH, CALIFORNIA, ASSIGNOR OF ONE-HALF TO
ZEBULON S. SKINNER, OF LOS ANGELES, CALIFORNIA.

FINGER RING.

Application filed June 7, 1921. Serial No. 475,611.

To all whom it may concern:

Be it known that I, CARLTON W. HOLMES, a citizen of the United States, residing in the city of Long Beach, and county of Los

Angeles and State of California, have invented certain new and useful Improvements in Finger Rings, of which the following is a specification.

My invention relates to finger rings, and more particularly to a new and improved method of mounting and securing jewels in a row, circumferentially on the outer periphery of the ring and at opposite sides of the main setting.

In order to explain my invention, I have shown one embodiment thereof in the accompanying drawings, in which,—

Figure 1 is a side elevation of a ring embodying my invention, partly in section; and Figure 2 is a top plan view thereof.

Referring to the drawings, 1 designates the ring body and 2 the ordinary setting. In the top of the ring body, at opposite sides of the setting 2, are groove-like seats, 3, 3, in which are set rows of small jewels, 4, 4, of bead-like construction, threaded on short wires 5, 5. The ring body is provided with a hole and a pocket, as at 6, and one end of the wire is formed into a knot or knob, 7, which seats closely in the pocket, while the other end of the wire, in the form shown for illustrative purposes, is bent

around a part of the setting, as at 8. Thus the two ends of the wire are secured to the ring and the bead jewels are thus securely held in place with no exposure of the means for holding them in place.

I am aware that slight changes can be made in the details of securing the ends of the wires and other minor details without departing from the spirit of the invention, and I do not, therefore, limit the invention, except as I may be limited by the hereto appended claim.

I claim:

A ring of the character shown having a ring body with a setting therein, said ring body increasing in thickness as it approaches the opposite sides of said setting and having circumferentially extending grooves in its top side at opposite sides of said setting, a series of jewels seated in said grooves, at each side of said setting, and securing wires for each set extending from the setting, through said jewels and at its end secured through an opening in the body of the ring, as shown and described.

Signed at Los Angeles, California, this 26 day of May, 1921.

CARLTON W. HOLMES.

In presence of—

W. R. LITZENBERG,
D. O. FAWCETT.
